UNITED STATES PATENT OFFICE.

BENJAMIN ANDREWS, OF PHILADELPHIA, PENNSYLVANIA.

IMPROVEMENT IN ARMY-TRUNKS.

Specification forming part of Letters Patent No. 33,628, dated November 5, 1861.

To all whom it may concern:

Be it known that I, BENJAMIN ANDREWS, of the city of Philadelphia, in the State of Pennsylvania, have invented a new and useful Improvement in Camp-Bedsteads; and I do hereby declare that the following is a full, clear, and exact description of the construction and operation of the same, reference being had to the annexed drawings, making a part of this specification, in which—

Figure 1 is a perspective view of the invention applied to a traveling-trunk and extended for use; Fig. 3, a vertical longitudinal section of the same as folded within the trunk, and Fig. 2 a vertical longitudinal section of the same removed from the trunk and supported in an extended position upon its legs as a bedstead.

Like letters indicate the same parts when in the different figures.

The nature of my invention consists in the peculiar construction and arrangement hereinafter described and specified, whereby a mattress and a suitable supporting frame or platform therefor are adapted to be inclosed together within the lid of a common traveling-trunk, so as to leave the main body of the interior of the said trunk unobstructed or unoccupied thereby, and also admit of the said mattress and platform being extended and supported either upon the opened trunk or upon the legs of the platform independently of the said trunk, so as to produce in either case an elevated and comfortable bedstead for camp-service.

In the drawings, A represents the mattress, B its supporting-platform, and C the traveling-trunk.

The mattress A, I generally make of curled hair inclosed in a case of soft leather and afterward tufted in the usual manner, as indicated in Fig. 1. Its supporting-platform B consists of a middle portion b' , whose width and length correspond with the width and length, respectively, of the interior of the trunk C, to which it is to be applied; a foot portion b'' , which is of the same width as and a little shorter than the middle portion b' , and to which latter it is hinged so that it can be either folded over upon it with the mattress A between, as seen in Fig. 3, or turned outward, as in Figs. 1 and 2, and a head portion

b''' , which is about half the length of b' and pivoted near to one end of the latter, so that it may be readily folded inward upon the same, as seen in Figs. 2 and 3, or outward, so as to rest in an inclined position upon the upper edge of b' , as seen in the perspective figure and also in dotted lines in Fig. 2. The middle portion b' of the said platform is fastened down upon the upper side of a tray or shallow box D, which rests loosely upon cleats e e, attached to the inner side of the trunk-body C, so that the lower edges of the said portion b' and of b'' when opened out shall be in the same plane with the upper edges of the body of the trunk, as seen in Figs. 1 and 3, and the part b'' is provided with a drop-leg f, which supports it when opened out and extended horizontally, as seen in Figs. 1 and 2, or lies flatly upon the upper side of b'' when the latter is folded down upon b' , as seen in Fig. 3.

The mattress A is nailed down fast to the inner side of b'' and also to a portion of that of b' , leaving about half the length of the said mattress free to be turned upward and outward, as seen in Fig. 2, to allow access to the lid g of the tray D, and also to permit the head portion b''' of the platform B either to be turned inward thereon, as seen in Figs. 2 and 3, or outward, so as to serve as a support to the head end of the mattress A, as indicated by the dotted lines in the same figure and fully shown in Fig. 1.

For the purpose of supporting the platform B and mattress A together at a suitable height above the ground when the same are separated from the trunk C, four legs h h are pivoted to the sides at points near the four corners of the tray D, so that the said legs can either be turned downward for the purpose, as seen in Fig. 2, or folded up close along its sides, as indicated by the dotted lines in Fig. 3.

In the operation of this invention, when it is desired to inclose it within the trunk, the different parts described are to be folded together in relation to each other in the manner seen in Fig. 3, and the lid C' of the trunk, being then shut down, receives within it the whole platform and mattress, leaving the interior of the tray D and of the body of the trunk C unobstructed thereby, and when it

is desired to use the invention as a bedstead, the lid C' of the trunk is to be fully raised, the portion b'' of the platform B turned outward and rested upon its drop-leg f, and the loose part of the mattress A then turned outward over upon it, as seen in Fig. 2. The head portion b''' of the platform B is now to be turned outward, so as to rest upon b' in the inclined position indicated by the dotted lines in the same figure, and finally the loose end of the mattress A returned, so as to rest extended upon them, as seen in Fig. 1, thus forming upon the open trunk a raised and comfortable bed; and when it is desired to have it a raised bed separate from the trunk it is only necessary to lift the platform and its attachments out and turn down the four legs h h, so that they, in connection with the drop-leg f, may support it, as seen in Fig. 2.

Having thus fully described my improved

camp-bedstead, what I claim as my invention, and desire to secure by Letters Patent, is—

1. The folding platform B, in combination with the mattress A, tray D, and drop-leg f, the same being constructed and arranged to operate together in combination with a trunk, whether closed or opened, substantially in the manner described and set forth, and for the purpose specified.

2. In combination with the said platform B, mattress A, tray D, and drop-leg f, constructed and arranged to operate as described, the legs h h, attached thereto so as to operate in the manner described and set forth, and for the purpose specified.

BENJN. ANDREWS.
